ATTORNEY

UNITED STATES PATENT OFFICE.

HENRY WALDORF, OF ST. LOUIS, MISSOURI.

ALUMINUM HEEL FOR LADIES' SHOES.

1,366,981.

Specification of Letters Patent.

Patented Feb. 1, 1921.

Application filed October 11, 1920. Serial No. 416,096.

To all whom it may concern:

Be it known that I, HENRY WALDORF, a citizen of the United States, residing in the city of St. Louis and State of Missouri, have 5 invented certain new and useful Improvements in Aluminum Heels for Ladies' Shoes, of which the following is a specification.

My invention relates to aluminum heels for ladies' shoes, and, has for its particular object to provide a comparatively simple and inexpensive means for retaining a leather plug in a socket in the tread end portion of the heel with the assistance of a screw, or equivalent fastening means.

15 A further object of my invention is to provide plug retaining means in the form of a plate held in position at the base of the socket by means of a plurality of integral upwardly extending fingers cast, or 20 anchored in the roof of the socket to hold the plate in fixed relation with the heel.

25 A further object of the invention is to provide the plate with a plurality of integral downwardly extending peripherally arranged locking fingers adapted to be bent inwardly over a plug when seated in the socket of the heel for firmly holding the plug in its socket.

With the above and other objects in view, 30 the invention consists in the novel construction of a plug retaining plate and manner of fixing same to the roof of a socket in the tread portion of a heel, as hereinafter fully described and finally pointed out in the 35 claims hereto appended.

Referring to the accompanying drawings forming a part of this specification wherein like characters of reference denote similar parts throughout the several views:

40 Figure 1, is a perspective view of the tread portion of a heel provided with a plug retaining plate in accordance with my invention.

Fig. 2, is a perspective view of the tread portion of a heel provided with a leather plug and clearly showing the manner in which I firmly retain the plug in its socket.

Fig. 3, is a sectional view of the tread portion of a heel clearly showing how the 50 plate is held in fixed relation to the roof of the socket.

Fig. 4, is a sectional view of the tread portion of a heel, showing a plug held in the socket of the heel and showing a tread 55 lift fixed to the plug.

Fig. 5, is a front elevation of the plug retaining plate.

Fig. 6, is a bottom plan view thereof.

Fig. 7, is a top plan view thereof.

Referring to the drawings, the reference character 1 indicates the tread portion of an aluminum heel for ladies' shoes. The tread portion 1 is provided with a socket 2 open at its lower end and bounded by a wall 3 having an inclined inner face 4. The upper end of the socket is closed by the roof 5.

In carrying out the aim of my present invention, I employ an aluminum plate 6, of a shape to conform to the base of the 70 socket 2, which shape is substantially semi-circular. The plate 6 is provided near its center with a plurality of suitable fingers 7, preferably V-shaped. The fingers 7 are punched out of the plate 6 and are bent 75 upwardly, as shown in Fig. 6. The fingers 7 of the plate 6 are cast to the roof 5 of the socket, as clearly shown in Fig. 3, which firmly holds the plate at the base of the socket 2 and in fixed relation with the heel. 80

The plate 6 is further provided with a plurality of outwardly and downwardly extending fingers 8. One of these fingers is preferably positioned at the straight side of the plate 6 while the other two are arranged on the curved edge of the plate so they will lie to the rear side of the plate. The outwardly extending portions 9 of the fingers 8 engage the inclined inner face 4 of the wall of the socket, as shown in 90 Fig. 1, thereby permitting a leather plug 10 to be easily and readily positioned in the socket 2, as is manifest. After the plug 10 has been positioned in the socket 2, the fingers 8 are bent inwardly to engage the 95 outer face of the plug, as clearly shown in Fig. 2, to firmly hold the plug in the socket 2. After the fingers 8 have been bent over into engagement with the plug 10, a suitable leather top lift 11 may be fixed to the leather 100 plug 10 by means of the usual nails 12.

It will be observed that there is plenty of open space between the fingers 8, after they are bent over into engagement with the plug to permit the nails 12 to enter the plug 10 105 as they are driven through the top lift 11.

From the foregoing description and the illustrations, it is evident that I provide a simple, inexpensive and practical means for securing a plug in the socket of an alumi- 110

num heel and that I accomplish this without the use of a screw, or equivalent fastening device that first requires drilling into the roof of the socket and then the use of 5 a screw, or the like.

The many advantages of the herein described invention will readily suggest themselves to those skilled in the art to which it appertains.

10 I do not desire to be understood as limiting myself to the exact details of construction and arrangement as herein described and illustrated, as it is manifest that variations and modifications may be made 15 without departing from the spirit and scope of my invention and the terms of the following claims, hence I wish it to be understood that I reserve the right to make any such changes, or modifications as may fairly 20 fall within the scope of the appended claims when fairly construed.

What I claim is:

1. In combination with a heel provided with a socket leading from the tread end 25 of the heel, a plate receivable in the socket and cast to the roof of the socket, a plurality of fingers extending from the plate and disposed beyond the lower face of the socket, and a plug carried in the socket, said 30 plug being retained in the socket by bend-

ing the free ends of said fingers over the other edge of the plug to engage the outer face of the plug.

2. In combination with a heel provided with a socket leading from the tread end of 35 the heel, a plate having upwardly extending fingers retained in said socket by being cast to the roof of the socket, a plug carried in the socket and flexible means carried by the plate for holding the plug in 40 the socket.

3. In combination with a heel provided with a socket leading from the tread end of the heel, a plug carried in said socket, a lift 45 fixed to said plug, a plate interposed between the plug and the roof of said socket, means for anchoring said plate to the roof of the socket, and means integral with the plate adapted to be clinched over the edge of the plug to hold the plug in the socket. 50

4. In combination with a heel provided with a socket leading from the tread end of the heel, a plug in said socket, and means anchored intermediate the inner face of the plug in the roof of the socket for holding 55 the plug in the socket.

In testimony whereof I have hereunto signed my name to the specification.

HENRY WALDORF.
